UNITED STATES PATENT OFFICE.

LIONEL NORMAN, OF WINCHESTER, MASSACHUSETTS.

PAPER PAIL.

1,160,527.

Specification of Letters Patent. Patented Nov. 16, 1915.

Application filed January 19, 1914. Serial No. 812,990.

To all whom it may concern:

Be it known that I, LIONEL NORMAN, a citizen of the United States, residing at Winchester, in the county of Middlesex and State of Massachusetts, have invented certain new and useful Improvements in Paper Pails; and I do hereby declare the following to be a full, clear, and exact description of the invention, such as will enable others skilled in the art to which it appertains to make and use the same.

The present invention relates to paper pails or similar paper vessels for storing or shipping edible or other products and has for its object to provide an improved vessel of this character having a cover which will securely and safely retain the contents without liability of leakage, but which can be readily removed to permit inspection or use of the contents.

With this object in view the invention consists in a paper vessel having its parts constructed and arranged in the improved manner hereinafter described and claimed.

The several features of the present invention and their advantages will be readily understood by those skilled in the art from an inspection of the accompanying drawings in which:

Figure 1 is a sectional elevation of a pail embodying the invention, the cover being shown detached from the body portion of the pail; and Fig. 2 is an underneath plan view of the cover illustrated in Fig. 1.

The body portion of the pail illustrated in the drawings is of usual or well-known construction and comprises inner and outer side walls 1 and 2 of paper, and a bottom 3 of paper provided with an upturned edge 4 received between the inner and outer walls. At its upper open end the body portion of the pail is provided with a non-metallic ring 5 of wood, leather board, fiber or other similar material, which is secured to the inner surface of the side wall in a suitable manner, but preferably by glue or other suitable cement in order to avoid perforating the side walls. This ring 5 is provided with an internal screw thread, as indicated at 6.

The cover of the pail illustrated in the drawing comprises a non-metallic ring 7 which is secured to a paper disk 8. The ring 7 is provided with an external screw thread indicated at 9 which fits the internal screw thread 6 on the ring 5. As illustrated in the drawings, the disk 8 projects beyond the ring

7 so as to form a shoulder which fits down against the upper edge of the wall of the body portion. Also in the construction illustrated in the drawing the cover comprises a second paper disk 10 which is secured to the ring 9 and spaced from the disk 8 so that the cover of the pail comprises two walls separated by an air space, and corresponds in this particular to the structure of the body portion. To receive and safely retain the disk 10, the ring 9 is recessed internally so as to provide a shoulder, indicated at 11, to receive the edge of the disk. To facilitate the application and removal of the cover the external surface of the disk 8 is illustrated in the drawing as provided with suitable finger engaging projections 12.

The construction illustrated in the drawing constitutes the best form of the invention which has yet been devised, but it is to be understood that except as defined in the claims, the invention is not limited to the construction and arrangement illustrated.

The nature and object of the present invention having been indicated, and the preferred form of the invention having been specifically described, what is claimed is:

1. A paper vessel having, in combination, a body, a non-metallic ring secured to the body at its open end and provided with a screw thread, and a removable and replaceable cover provided with a non-metallic screw thread fitting the screw thread on the body.

2. A paper vessel, having in combination, a body, a non-metallic ring secured to the body at its open end and provided with a screw thread, and a removable and replaceable cover comprising a paper disk, and a non-metallic ring secured to the disk provided with a screw thread fitting the screw thread on the body.

3. A paper vessel, having in combination, a body, a non-metallic ring secured within the body at its open end and provided with an interior screw thread, and a removable and replaceable cover comprising a paper disk, and a non-metallic ring secured to the disk provided with an exterior screw thread fitting the screw thread on the body.

4. A paper vessel, having in combination, a body, a non-metallic ring secured to the body at its open end provided with a screw thread, and a removable and replaceable cover comprising two separated paper disks, and a non-metallic ring secured to the disks

provided with a screw thread fitting the screw thread on the body.

5. A paper vessel, having in combination, a body, a non-metallic ring secured within the body at its open end and provided with an interior screw thread, and a removable and replaceable cover comprising a paper disk, a non-metallic ring secured to the disk within its edge so as to leave the edge protecting over the wall of the body, said ring

being provided with an exterior screw thread fitting the screw thread on the body, and a second paper disk received in an internal recess in the ring of the cover and separated from the first mentioned disk.

LIONEL NORMAN.
